UNITED STATES PATENT OFFICE.

CHARLES H. SHEPARD, OF BROOKLYN, NEW YORK, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 737,163, dated August 25, 1903.

Original application filed February 6, 1902, Serial No. 92,851. Divided and this application filed May 29, 1902. Serial No. 109,521. (No model.)

To all whom it may concern:

Be it known that I, CHARLES H. SHEPARD, a citizen of the United States, and a resident of the borough of Brooklyn, city of New York, in the county of Kings and State of New York, have invented certain new and useful Improvements in Type-Writing Machines, of which the following is a specification.

This case is a division of my application filed February 6, 1902, Serial No. 92,851.

My present invention relates to "case-shifting" and line-lock mechanisms for type-writing machines.

It has been difficult heretofore when operating a type-writing machine at high speed to so time the successive operations of the shift-key that the upper and lower case printing characters will appear in proper alinement. If, for instance, there is a sluggish movement of the shifting mechanism or a premature operation of a type-key, the impression made before the completion of the shifting operation is either out of alinement or a blurred and imperfect impression is produced upon the paper, and in some instances the impression will include a part of the upper-case and a part of the lower-case character. In correcting such mistakes the appearance of the page is marred and much time and labor consumed. Still other faulty operations are liable to occur in some type-writing machines heretofore devised, such as the clashing or interlocking of the type-carriers or other parts.

One of the objects of my present invention is to overcome the difficulties above referred to and to provide at the same time simple and efficient line-lock mechanism whereby the type-carriers may be automatically locked out of operation when an end of a line is reached.

To the above and other ends which will appear in the following description my invention consists in the novel constructions and arrangements and combinations of parts to be hereinafter described, and particularly pointed out in the appended claims.

In the accompanying drawings, wherein like reference characters indicate corresponding

parts in the various views, Figure 1 is a vertical sectional view, partly in section, of one form of type-writing machine embodying my invention, the section being taken from front to rear of the machine. Fig. 2 is a like view of the same, showing a different disposition of the parts. Fig. 3 is a detail isolated diagrammatic perspective view of the case-shifting mechanism, together with the means employed for preventing an operation of the type-carriers while the case-shifting mechanism is being operated, as well as the line-lock mechanism, which cooperates therewith. Fig. 4 is a detail plan view of a portion of the dog-rocker frame, to be hereinafter more fully described. Fig. 5 is a detail isolated side view of a portion of the blocking and line-lock mechanism. Fig. 6 is a side view of one of the blocking fingers or catches and the arm which carries it.

In the various views parts have been omitted or broken away to more clearly illustrate other features of the structure.

I have shown my invention applied to a No. 6 Remington machine, though it should be understood that the invention or any one or more of the separate features thereof may be applied to any other character of type-writing machine.

The frame 1 is surmounted by a top plate 2, which supports upright studs 3 4, to which the traverse-rods 5 6, respectively, are connected. The usual carriage 7 moves from end to end of the machine on the traverse-rods and carries a platen-frame 8, in which a platen 9 is mounted to revolve. The front end of the platen-frame is supported upon a shift-rod 10, which is connected to the upper ends of upright shift-arms 11 12, located near the opposite ends of the machine and secured to a rock-shaft 13, that is adapted to rock in bearings formed in arms or supports 14, which depend from the top plate 2. The shift-rod 10 is moved transversely, as will hereinafter more clearly appear, to move the platen-frame and platen in a direction transverse to its feed to change the "case" position thereof. This transverse movement of the platen and its frame is limited by stop-

pins 15, carried in the usual manner by the carriage 7 at each end thereof and which co-operate with each end of a projecting pivot rod or shaft 16, which pivotally connects the 5 platen-frame to the carriage 7 through the usual links 17.

Character key-levers 18 are fulcrumed at 19 in the frame 1 of the machine and are provided with finger-keys 20 and restoring-springs 21. Each key-lever 18 is connected to a link 22, which is in turn connected to a type bar or carrier 23. A spacing key or bar 24 is connected at each end to a key-lever 25, both of which are likewise fulcrumed at 19 15 upon opposite sides of the keyboard and are provided with restoring-springs 21. The parts thus far described constitute a portion of the well-known No. 6 Remington machine, and a more elaborate description thereof is 20 deemed unnecessary.

Extending transversely beneath the key-levers 18 and 25 is the usual universal bar 30, which has connected thereto at each end a link 31, the links being connected at their 25 upper ends 32 to a transversely-extending bar 33, which is carried by an arm 34 that extends from a rock-shaft 35, mounted in bearings in the arms 36, that are secured at 37 to a plate-like bracket 38, which extends 30 downwardly from the top plate 2. The rock-shaft 35 is restored to the normal position by a spring 39, which is secured at one end 40 to the bracket 38 and is secured at its opposite end 41 to the rock-shaft. Extending rearwardly from the rock-shaft 35 is a crank-arm 35 42, which is pivoted at 43 to a link 44, that in turn is pivoted at 45 to a two-arm lever 46, that is pivoted at 47 to a depending bifurcated bracket-arm that extends downwardly 40 from a bracket-plate 48, that is secured by screws 49 to studs 50, which project from the plate-like bracket 38. The rear end of the two-arm lever 46 is pivoted at 51 to a link 52, which actuates suitable feed-dogs 53, that 45 co-operate with an escapement-wheel 54, operatively connected to a shaft that revolves in a bearing 55, secured to the top plate and carrying at its forward end a feed-pinion 56, that meshes with a feed-rack 57, carried by 50 the carriage in the usual manner.

Referring particularly to Fig. 3, it will be observed that the shifting arm 11 at the right-hand side of the machine extends downwardly beyond its pivotal center and forms two arms 55 93 and 94. The arm 94 is pivoted at 95 to a link 96, which has its opposite end pivoted at 97 to a shift-key 98, which is provided with the usual finger-key 99 and is pivoted at 100 (see Fig. 2) to an upwardly-extending inverted-U-shaped bracket 101, that is secured to an arm 102, which projects laterally from the frame 1 of the machine. The shifting arm 12 at the opposite side of the machine is provided with a depending portion 103, which 60 65 has a link 104 pivoted thereto at 105. A screw 106 projects through a slot 107 in this link and is threaded into an opening in the

part 103. The pin 106 thus constitutes a stop which limits the movement in opposite directions of the link with relation to the part 103. 70 The upper end of the link 104 is pivoted at 108 to a connecting rod or link 109, that is pivoted at 110 to a U-shaped yoke 111, that surrounds a shift-key lever 112, which is pivoted at 113 to a fixed arm 102^a of the machine 75 in the same manner as the shift-key 98 and is provided with a finger-key 114. The depending part 103 likewise has pivoted thereto at 115 a shifting piece 116, that is apertured at 117 for the reception of a pin or screw 80 118, that is secured to the piece 103 and projects through said slot or aperture 117 and limits the movement of the shifting piece with relation to the part 103. One arm 119 of this shifting piece is provided with a laterally-projecting finger or pin 120, which extends into an opening 121 in the link 104. Another arm 122 of the shifting piece has connected thereto at 123 a spring 124, the lower end 125 of which is secured to a screw-eye 126, that 90 is fastened to a fixed portion of the machine. 85

From the foregoing description it will be understood that when the parts are in the position represented in Fig. 3 of the drawings the spring 124 will exert a pressure to maintain the shift-rod 10 in the foremost position, where the platen is maintained in a position to co-operate with the lower-case type on the type-bars. When, however, the finger-piece 127 is moved up, such movement is effective to turn the shifting piece 116 on its pivot 115, thereby moving the upper end 123 of the spring to the opposite side of the pivot 115, at the same time moving the upper end of the link 104 forward to the opposite side 105 of the pivot 105 thereof. The spring 124 is at this time effective to maintain the shift-rod 110 in the rearward position, at which time the platen is in a position to receive the impact of the upper-case type on the type-bars. When the parts are in the position represented in Fig. 3, the finger-keys 99 and 114 are adapted to momentarily shift the shift-rod 10 and the platen which is operatively connected thereto to change the printing position thereof from lower to upper case. When, however, the finger-piece 127 has been moved upwardly, as previously described, a depression of the shift-key is effective to temporarily shift the platen from the upper-case 110 printing position to the lower-case printing position. The case-shifting mechanism thus far described constitutes a part of the well-known No. 6 Remington type-writing machine and need not be further described. 115

The depending arm 93, hereinbefore referred to, has a rearwardly-extending rod 128, pivoted thereto at 129. This rod is provided with a laterally-extending pin 130, that projects into an inclined slot 131 in an upwardly-extending arm 132, which is secured to a rock-shaft 133. This arm has pivoted thereto at 134 a blocking piece or finger 135, which is normally maintained in a fixed relation to 125

the arm 132 by a spring 136, which is connected at one end to the finger 135 and is secured at its opposite end 137 to the arm 132. The rock-shaft 133 is provided near its opposite end with a second upwardly-projecting arm 138, that corresponds to the arm 132, and, like said arm, it has pivoted thereto at 139 a blocking piece or finger 140, which is normally maintained in a fixed position with relation to the arm by a spring similar to the spring 136, hereinbefore described. The rear end of the rod 128 is pivoted at 141 to an upwardly-extending link 142, which is pivoted at its upper end 143 to one arm of a bell-crank lever 144. The other arm of this bell-crank lever is preferably rounded at its end 145 and is seated within a slot of a yoke 146, which projects downwardly from a rack 147. This rack is provided with reduced cylindrical ends 148, (see Fig. 3,) that are seated in bearing-openings in the supporting-studs 3. The cylindrical end 148 at the left-hand end of the machine (looking from the front) extends through the stud 3, and a leaf-spring 149, which is secured to the top plate at 150, bears against the free end of said pin and tends to maintain the rack toward the right, but permits under conditions which will hereinafter appear a slight longitudinal movement of the rack. The rack 147 carries an adjustable stop or line-lock abutment 151, with which a cooperating trip or abutment 152, carried by the carriage, is adapted to contact in the travel of the carriage from right to left or in the direction of its feed.

In the operation of the case-shifting mechanism and the automatic lock therefor the blocking-fingers 135 and 140 are normally maintained either just forward or back of the transverse bar 33, or what may be termed the "dog-rocker" frame. When the parts are in the position to write lower-case characters, as shown in Fig. 3, a depression of either of the temporary shift-keys 99 or 114 or an upward movement of the permanent shift-key 127 will cause the shift-rod 10 to be moved toward the rear of the machine. This movement of the shift-rod and the parts connected thereto will cause the rod 128 to be moved forward, together with the arm 132, connected to said rod, thus producing a rocking movement of the shaft 133, which effects a like movement of the arm 138 at the other side of the machine. The forward movements of the arms 132 and 138 bring the blocking-fingers into the path of the transverse bar 33, and it cannot be depressed until the arms 132 and 138, together with their blocking-fingers, have completed their forward movement. At the completion of the forward movement of these parts the blocking-fingers will have just cleared the transverse bar 33 and will be maintained in the spaces formed between the projecting arms 153 and the transverse bar to which they are secured. It will be understood that if the operator attempts to depress a character-key or the

space-bar during this shifting operation, the blocking-fingers will arrest a movement of the transverse bar 33, thus preventing an actuation of the type-bars or escapement mechanism. As soon, however, as the shifting movement has taken place the blocking-fingers are clear of the transverse bar 33 and the fingers 153 connected thereto, and the operator may at this time depress the character-keys or the spacing-key. When the permanent shifting device is moved by raising the finger-piece 127, so that all upper-case characters will be written, the arms 132 and 138 and the blocking-fingers carried thereby will be moved forward to the position represented in full lines of Fig. 2 of the drawings. A depression of the temporary shift-key 114 or a movement of the finger-piece 127 to the position shown in Fig. 3 will at this time cause the blocking-fingers to be moved with their arms toward the rear of the machine and across the path of movement of the transverse bar 33 in order to prevent a depression thereof until the completion of the case-shifting movement.

Should the operator attempt to actuate the finger-piece 127 on either of the shift-keys 99 or 114 when a character-key or the space-key is partly or fully depressed, it will merely result in the blocking-fingers being brought into engagement with either side of the transverse bar 33 or the arms 153 thereof, and the pivoted fingers will yield against the tension of their springs, so that no injury can be done either to the rocker-frame or the fingers. As soon as the finger of the operator is removed from the keys the blocking-fingers will resume their normal positions with relation to the arms which carry them, the springs of said blocking-arms restoring them to the normal position.

It will be understood from the foregoing description that a type impression cannot be made during the transverse shifting movements of the platen, so that it becomes impossible for a double or blurred impression to be produced or for the upper-case impressions to appear out of alignment with the lower-case impressions. Thus no matter how high the speed of operation or how poorly timed are the successive operations of the shift-keys and type-keys it is impossible for the operator to produce the faulty work hereinbefore referred to.

When the line-lock abutment 152 on the carriage contacts with the coöperating abutment 151, the tension of the carriage-spring will move the abutment 151, together with the rack 147, which carries it, in a longitudinal direction and against the tension of its spring 149. The effect of this movement of the rack 147 is to rock the bell-crank lever 144 on its pivot, thus raising the rear end of the rod 128 around the forward pivot 129 thereof. This elevation of the rear end of the rod is effective to transmit a forward movement to the arm 132 through the pin-

- and-slot connection 130 131 and through the rod-shaft 133 to the corresponding arm 138. If the parts are in the lower-case printing position, (represented in Fig. 1,) the blocking-fingers 135 and 140, carried by these arms, will be projected beneath the transverse bar 33 and thus prevent the depression thereof. If, however, the parts are in the upper-case printing position, then the arms 132 and 138 will normally assume the position shown in full lines in Fig. 2 and the actuation of the line-lock mechanism will move the arms forward, together with their blocking-fingers, to the position shown in dotted lines in Fig. 2, where they will coöperate with the fingers 153, carried by the transverse bar 33, to prevent a depression of the bar and an actuation of any of the character-keys or the spacing-key.
- From the foregoing description it will be seen that the instrumentalities which enter into the mechanism for automatically preventing an actuation of any of the character-keys or the space-key during the shifting operation from the lower-case printing position to the upper-case printing position, or vice versa, likewise enter into and constitute a part of the line-lock mechanism, so that the one set of mechanism acts in a twofold capacity.
- Should the operator desire to write one or more characters after the line-lock mechanism has been operated in order to insert one or more additional characters, it is merely necessary to push in the button 154, that extends forwardly from the top plate 2 of the machine and which is connected to a rearwardly-extending rod 155, that is guided in suitable bearings beneath the top plate and is provided at its rear end with an upwardly-extending finger 155', that is seated in a longitudinally-extending recess or slot in an arm 156, that is secured to and projects downwardly from the rack 147. The effect of this movement is to rock the rack 147, thus carrying the stop or line-lock abutment 151 out of the path of the coöperating abutment on the carriage, and the spring 149 will restore the rack to the normal position, thereby releasing the line-lock to permit one or more additional characters to be written. When the finger-piece or button 154 is released, it, together with the parts connected thereto, are restored to the normal position by a coiled spring 157, which bears at one end against the rear face of the button and at its opposite end against one of the bearings 153.
- While I have shown and described with considerable detail one form of type-writing machine embodying my invention, it should be understood that various changes may be made without departing from the spirit of my invention and that the different features of the invention as defined in the claims may be used separately or may be combined in a single structure.

What I claim as new, and desire to secure by Letters Patent, is—

1. In a type-writing machine, the combination of a series of types, a platen, means for impressing the types, a case-shift mechanism, means for blocking the type-impressing movements during the operation of the case-shift mechanism, and means for automatically actuating said blocking means when an end of a line is reached. 7c

2. In a type-writing machine, the combination of a series of types, a case-shift mechanism, means controlled by said case-shift mechanism for blocking the printing movements of the types, and means for automatically actuating said blocking means when an end of a line is reached. 80

3. In a type-writing machine, the combination of a series of keys, a series of types, a platen, means for causing a relative case-shifting movement between said platen and all of said types, means for blocking the printing movements of said types when a relative case-shifting movement between the platen and all of the types is effected, and means for automatically actuating said blocking means when an end of a line is reached. 85

4. In a type-writing machine, the combination of a series of types, a platen, means for shifting said platen, means for blocking the operation of said types when the shifting movement of the platen takes place, and means for automatically actuating said blocking means when an end of a line is reached. 95

5. In a type-writing machine, the combination of a type mechanism, a case-shift mechanism, a device connected to said case-shift mechanism and caused at the operation of the latter to get into the path of and block the movement of a part which is moved at the printing stroke of the type, and means for automatically moving said device to the blocking position when an end of a line is reached. 105

6. In a type-writing machine, the combination of a series of types, a series of keys therefor, a carriage, carriage-escapement devices operated by said keys, a platen, a case-shift mechanism, a catch operatively connected to said case-shift mechanism and arranged to block the operation of said carriage-escapement devices and hence of said keys, and independently automatically operated means for moving said catch to the blocking position 115 when an end of a line is reached. 120

7. In a type-writing machine, the combination of a series of types, a series of keys, a carriage, an escapement mechanism therefor including a dog-rocker operated by said keys, 125 a case-shift mechanism, a catch connected to said case-shift mechanism and arranged in proximity to said dog-rocker and adapted to block its movement and independently automatically operated means for moving said catch to the blocking position when an end 130 of a line is reached.

8. In a type-writing machine, the combination of a platen, a series of types, a series of keys, mechanism for causing a relative shifting movement between said types and said platen, a vibratory device connected to said shift mechanism, a part controlled by the keys and arranged to be intercepted by said vibratory device, and means for automatically moving said part to the intercepting position when an end of a line is reached.

9. In a type-writing machine, the combination with a series of types and a platen, of a normally inactive catch adapted to block a part that moves in unison with all the types, a shift-key mechanism, and connections between said shift-key mechanism and said catch, and independently automatically operated means for moving said catch to the blocking position when an end of a line is reached.

10. In a type-writing machine, the combination of a series of types, a series of key-levers connected thereto, a platen-carriage, escapement devices for said carriage controlled by said keys, a rock-shaft, catches thereon, a link, a platen-shifting frame to which said link is connected, and means for automatically actuating the catches when an end of a line is reached.

11. In a type-writing machine, the combination of a series of types, a platen, a case-shift mechanism, a yielding finger connected to said case-shift mechanism and arranged out of the path of a part which moves in unison with the types, means for causing said finger to intercept said part during the operation of the case-shift mechanism, and independent means for moving said finger to the intercepting position when an end of a line is reached.

12. In a type-writing machine, a catch connected to and moving with a case-shifting mechanism and comprising two parts, one yieldingly pivoted upon the other and occupying a normal position just out of the path of a part which moves in unison with type-impressing devices, and means for moving said catch into the path of the part which moves in unison with the type-impression devices when an end of a line is reached.

13. In a type-writing machine, the combination with a series of types, a platen, a carriage, escapement devices including a dog-rocker, a platen-shifting mechanism, of rock-shaft, arms thereon, yielding fingers carried by said arms and adapted to be moved into the path of said dog-rocker, a link connecting one of said arms to the case-shift mechanism, and means for automatically moving said yielding fingers into the path of the dog-rocker when the carriage reaches an end of a line.

14. In a case-shifting and key-blocking and line-lock mechanism, the combination of rock-shaft, arms thereon, fingers pivoted on said arms, springs which maintain a normal fixed relation between said fingers and arms, means

connected to the case-shift mechanism for rocking said shift and means connected to said shaft-rocking means for moving it automatically when an end of a line is reached.

15. In a type-writing machine, the combination of a platen, a carriage, type-carriers, finger-keys for said type-carriers, means for moving said platen transversely for shifting the case position thereof, means for automatically locking the finger-keys against printing movement during the transverse shift of the platen, and means controlled by the carriage and operatively connected to said locking means for actuating it when the carriage reaches an end of a line.

16. In a type-writing machine, the combination of a platen, a carriage, type-carriers, finger-keys for said type-carriers, means for moving said platen transversely for shifting the case position thereof, a bar connected to said platen-shifting means and adapted to move in unison therewith, means operatively connected to said bar and controlled by the movement thereof for locking the parts against printing movement, and means controlled by the feed movement of the carriage for affording a movement of the bar and the locking means controlled thereby when the carriage reaches the end of a line.

17. In a type-writing machine, the combination of a platen, a carriage, type-carriers, finger-keys for said type-carriers, means for moving said platen transversely for shifting the case position thereof, means for automatically locking the finger-keys against printing movement during the transverse shift of the platen, and adjustable means controlled by the feed movement of the carriage and operatively connected to said locking means, for actuating said locking means when the carriage reaches an end of a line as determined by the adjustment of said adjustable means.

18. In a type-writing machine, the combination of a platen, a carriage, type-carriers, finger-keys for said type-carriers, means for moving said platen transversely for shifting the case position thereof, a bar connected to said platen-shifting means and adapted to move in unison therewith, means operatively connected to said bar and controlled by the movement thereof for locking the parts against printing movement, independent adjustable means operatively connected to said bar, and a trip carried by the carriage and cooperating with the adjustable means to afford a movement of the bar and the locking means controlled thereby when the carriage reaches the end of a line.

19. In a type-writing machine, the combination of a platen, a carriage, type-carriers, finger-keys for said type-carriers, means for moving said platen transversely for shifting the case position thereof, a bar connected to said platen-shifting means and adapted to move in unison therewith, means operatively connected to said bar and controlled by the movement thereof for locking the parts

against printing movement, means controlled by the feed movement of the carriage for affording a movement of the bar and the locking means controlled thereby when the carriage reaches the end of a line and hand-operated means for releasing the locking means after the carriage reaches the end of a line.

5 Signed at the borough of Manhattan, city

of New York, in the county of New York and State of New York, this 26th day of May, A. 10
